SPOT FREQUENCY OSCILLATOR SYSTEM

George F. Moynahan, Jr., Sacramento, Calif.

Application March 5, 1946, Serial No. 652,211

3 Claims. (Cl. 250—36)

(Granted under the act of March 3, 1883, as
amended April 30, 1928; 370 O. G. 757)

1

The invention described herein may be manufactured and used by or for the Government for governmental purposes, without the payment to me of any royalty thereon.

My invention relates to electron tube oscillators, particularly to novel means for stabilizing the operating frequency thereof at one or more frequencies.

Continuously tunable superheterodyne receivers are very often unstable in tuning due primarily to "creepage" of the local oscillator frequency during changes in ambient temperature, particularly during the warm-up period, changes in line voltage, etc. For improving stability automatic frequency control methods can be used or crystals can be incorporated in the circuit at certain "spot" frequencies. These expedients cannot, however, be applied to an existing receiver without considerable rebuilding.

It is a principal object of my invention to provide novel and simple means whereby a continuously tunable oscillator can be rendered stable at selected "spot" frequencies.

It is a further object of my invention to provide a stabilizing circuit for an oscillator, such as the local oscillator of a superheterodyne receiver, which can be readily attached with a minimum of alteration of the existing circuit.

In accordance with my invention an auxiliary crystal-controlled oscillator circuit, having several selectable crystals, is interconnected at a point in the existing oscillator of the receiver. Switch means is provided in the auxiliary circuit whereby in one position of the switch the existing oscillator functions normally. At other positions, the auxiliary oscillator, functions to operate at a desired spot-frequency or a subharmonic thereof, and the existing oscillator circuit is reconstituted either as a buffer amplifier, if the crystal operates at the fundamental frequency, or as a frequency multiplier, if the crystal operates at a subharmonic.

For a better understanding of the invention together with other and further objects thereof, reference is had to the following description, taken in connection with the accompanying drawing which shows a schematic circuit of the invention.

In the drawing, the portion of the circuit shown within the dot-dash enclosure 8 represents a standard oscillator circuit such as is used as the local oscillator of a conventional superheterodyne receiver. This oscillator comprises a triode 10 connected to a tank circuit 12, including a continuously variable tuning condenser 14 and a

2

tapped coil 16 connected in the plate and grid circuits to provide feedback. Condensers 18 and 20 serve as series and parallel padder condensers, respectively. Condenser 22 and resistor 24 serve as a grid condenser and grid leak. The lead to the grid is broken and connected to one section 10 of a three-section switch for a purpose to be described hereinafter. Injection of oscillations into the mixer of a superheterodyne receiver is accomplished by a connection from the cathode of tube 10 to the mixer cathode.

The remainder of the circuit, i. e., the elements outside the dot-dash enclosure 8, constitutes the spot-frequency stabilizer which is the main feature of my invention. It serves to stabilize the tuning of the local oscillator at selected points of the tuning range of condenser 14. The stabilizer may be built as a separate unit or incorporated as an integral part of the receiver.

The stabilizer is a crystal-controlled oscillator circuit of the Pierce type, and includes a tube 30 having a resistor 38 between its grid and cathode, and a load resistor 42 in its plate circuit.

Between the grid and plate of tube 30 is adapted to be interposed one of a plurality of crystals 32—36, tuned to different frequencies, by means of one section 50 of the three-section switch, of which the other two sections are labelled 60 and 70, all three sections being uncontrolled as indicated by the broken line. Switch section 60 is interposed in the connection between the grids of tubes 10 and 30. Switch section 70 also serves to connect into the circuit a small auxiliary padder condenser 40 in certain of its positions.

The above-described circuit functions as follows:

With the switches in position 1, all crystals 32—36 are disconnected, tube 30 and padder condenser 40 are disconnected, and the grid of tube 10 is connected to the tank circuit 12, whereby the circuit 8 functions in its normal manner as the local oscillator of the receiver.

With the switch sections in any of positions 2—6, the grid of tube 10 is disconnected from the tank circuit by switch section 70, whereby it ceases to oscillate. The switch also connects the auxiliary padder condenser 40 across the tank circuit to compensate for the removal of the tube and lead capacities from the circuit so that the tank circuit calibration is not disturbed, whereby it will still track with the tuned radio-frequency circuits of the receiver. Switch section 50 connects one of the crystals 32—36 between the plate and grid of tube 30, whereby it begins to oscillate at the selected crystal frequency. Finally, switch

section 60 connects the grid circuit of oscillator tube 30 to the grid of tube 10, whereby the latter functions as a buffer amplifier having a tuned load circuit.

Each of crystals 32-36 may be tuned to a different spot-frequency. Each crystal may operate at the fundamental, whereby tube 10 acts as a tuned buffer amplifier, or, it may be tuned to a subharmonic of the desired spot-frequency, whereby tube 10 operates as a frequency multiplier or harmonic amplifier or generator tuned to the desired harmonic which constitutes the "spot" frequency.

When the oscillator 8 is functioning normally, i. e., when the spot-frequency circuit and its crystals are disconnected, there still may be a tendency to lock-in when the oscillator is tuned near the crystal frequency due to capacitative coupling between the oscillator circuit and the crystal. This can be avoided by shielding the switch units or by adding a switch section which will ground the crystals when not in use.

While there has been described what is at present considered a preferred embodiment of the invention, it will be obvious to those skilled in the art that various changes and modifications may be made therein without departing from the invention, and it is aimed in the appended claims to cover all such changes and modifications as fall within the true spirit and scope of the invention.

I claim:

1. The method of stabilizing an electron tube oscillator, having a load circuit which is tunable over a predetermined frequency range, at at least one frequency within said range, comprising the steps of altering the circuit of said oscillator to function as a radio-frequency amplifier tuned by said load circuit, tuning said load circuit to said one frequency, and impressing stable oscillations upon said amplifier, said one frequency having a harmonic relation to said stable oscillations.

2. In the operation of a superheterodyne receiver including a local electron tube oscillator having a load circuit which is continuously tunable over a predetermined frequency range, the method of stabilizing the tuning of said local oscillator of one frequency at said range, comprising the steps of altering the circuit of said oscillator to function as a radio-frequency amplifier tuned by said load circuit, tuning said load circuit to said one frequency, and impressing stable oscillations upon said amplifier, the frequency of said oscillations being equal to said one frequency.

3. In the operation of a superheterodyne receiver including a local electron tube oscillator having a frequency determining circuit which is continuously tunable over a predetermined frequency range, the method of stabilizing the tuning of said local oscillator at one frequency of said range, comprising the steps of altering the circuit of said oscillator to function as a harmonic generator tuned by said circuit, tuning said circuit to said one frequency, and impressing crystal-controlled oscillations upon said generator to stabilize it at said one frequency, the frequency of said oscillations being equal to a subharmonic of said one frequency.

4. An oscillator network comprising first and second electron tubes, a continuously-tunable circuit for said first tube, means to connect a utilization circuit to said first tube, a stable, fixed resonating means connected to said second tube, and selective means to either render said first tube oscillating and disable said second tube or

to cause said second tube to generate oscillations which are impressed upon said first tube.

5. An oscillator network comprising first and second electron tubes, a continuously-tunable circuit for said first tube, a utilization circuit coupled to said tunable circuit, at least one stable resonating means connected to said second tube and tuned to a subharmonic of one frequency within the range of said tunable circuit, and 10 switch means so connected in said network that, in one position, it causes said first tube to oscillate and disables said second tube, and, in another position, it causes said second tube to generate oscillations and reconnects said first tube so that 15 it functions as a harmonic generator controlled by said oscillations.

6. A local oscillator network for a superheterodyne receiver comprising first and second electron tubes, a continuously-tunable circuit, 20 means adapted to couple the input and output circuits of said first tube to said tunable circuit in feedback relation, a plurality of piezoelectric crystals adapted to be selectively connected to said second tube to cause it to oscillate at the frequency of one of said crystals, and a multiple-position switch so connected in said network that, in one position, it renders said first tube oscillating and disables said second tube, and, in any other position, it connects one of said crystals 25 to said second tube to cause it to oscillate at the crystal frequency, disables the feedback relation of said first tube, and connects the grid of said first tube to the output circuit of said second tube, whereby said first tube acts as a buffer 30 amplifier tuned by said tunable circuit.

7. A local oscillator network for a superheterodyne receiver comprising first and second grid-controlled electron tubes, a continuously-tunable circuit, a utilization circuit coupled to said tunable circuit, means adapted to couple the grid and plate circuits of said first tube to said tunable circuit in feedback relation, a plurality of piezoelectric crystals adapted to be selectively connected to said second tube to cause it to oscillate at the frequency of one of said crystals, 40 and a multiple-position switch so connected in said network that, in one position, it renders said first tube oscillating and disconnects said second tube and said crystals, and, in any other position, it connects one of said crystals to said second tube to cause it to oscillate at the crystal frequency, disconnects the grid of said first tube from said tunable circuit and connects it to an oscillation 45 circuit of said second tube, whereby said first tube acts as a buffer amplifier, and a reactance adapted to be connected to said tunable circuit by said switch in said other position to compensate for changes in the effect of interelectrode 50 capacity of said first tube.

8. A local oscillator network for a superheterodyne receiver comprising first and second grid-controlled electron tubes, a continuously-tunable circuit, a utilization circuit coupled to said tunable circuit, means adapted to couple the grid and plate circuits of said first tube to said tunable circuit in feedback relation, a plurality of piezoelectric crystals respectively tuned to a subharmonic of a different frequency within the 55 range of said tunable circuit and adapted to be selectively connected to said second tube to cause it to oscillate at the frequency of one of said crystals, a multiple-position switch so connected in said network that, in one position, it renders said first tube oscillating and disconnects said second tube and said crystals, and, in any other 60 position, it connects one of said crystals to said second tube to cause it to oscillate at the frequency of one of said crystals, a multiple-position switch so connected in said network that, in one position, it renders said first tube oscillating and disconnects said second tube and said crystals, and, in any other 65 position, it connects one of said crystals to said second tube to cause it to oscillate at the frequency of one of said crystals, a multiple-position switch so connected in said network that, in one position, it renders said first tube oscillating and disconnects said second tube and said crystals, and, in any other 70 position, it connects one of said crystals to said second tube to cause it to oscillate at the frequency of one of said crystals, a multiple-position switch so connected in said network that, in one position, it renders said first tube oscillating and disconnects said second tube and said crystals, and, in any other 75 position, it connects one of said crystals to said second tube to cause it to oscillate at the frequency of one of said crystals.

position, it connects one of said crystals to said second tube to cause it to generate oscillations at the crystal frequency, disconnects the grid of said first tube from said tunable circuit and connects it to an oscillation circuit of said second tube, whereby said first tube acts as a harmonic amplifier controlled by said oscillations, and a capacity adapted to be connected across to said tunable circuit by said switch in said other position to compensate for changes in the effect of interelectrode capacity of said first tube.
